(57) **CLAIM**

The ornamental design for a multi-functional sharpener for tools and blades, as shown and described.

DESCRIPTION

FIG. 1 is a top perspective view of the multi-functional sharpener for tools and blades showing my design.

FIG. 2 is a side elevation view thereof;

FIG. 3 is an opposite side elevation view thereof;

FIG. 4 is a front elevation view thereof;

FIG. 5 is a rear elevation view thereof;

FIG. 6 is a top plan view;

FIG. 7 is a bottom plan view; and,

FIG. 8 is a bottom perspective view showing elements of the sharpener in an extended position.

The device sharpens tools and blades, such as knife blades.
